United States Patent Office.

ROLAN DAILY, OF CANAL TOWNSHIP, PENNSYLVANIA.

Letters Patent No. 75,738, dated March 24, 1868.

IMPROVED CAR-COUPING.

The Schedule referred to in these Letters Patent and making part of the same.

TO ALL WHOM IT MAY CONCERN:

Be it known that I, ROLAN DAILY, of Canal township, in the county of Venango, State of Pennsylvania, have invented a new and improved Self-Acting Car-Coupling; and I do hereby declare that the following is a full and exact description of the same, reference being had to the accompanying drawings, and the letters of reference marked thereon.

Figure 1 is a side view of my coupling.

A is the shaft of the "draw-head," by which it is attached to the car in the usual manner. G, better shown at Figure 5, is an iron frame, through which the draw-head shaft A passes. This frame is bolted on the bottom of the car. 2 3 4 5 are spiral springs, which support the "draw-head" shaft A, giving it at the same time a freedom of motion to accommodate itself to the motion of the cars. D is a lever, which, when raised, may be kept in any desired position by the "ratchet" W. B is a stationary "link" or arm, bolted on the coupling by bolts 6 7. C is a slot, for a movable coupling-link of the common form, and F a common coupling-pin. These may be used when it is not desired to use the arm B, so that a car with my coupling on may be coupled to a car with a common coupling.

Figure 2 is a top view, showing the slot C and portion of the common coupling-pin F.

Figure 3 is a view of the under side, showing the internal construction of my coupling.

S is a coupling-pin, attached to the bent lever R. n is a catch, thrown towards the lever R by the spiral spring O. m is a "trigger"-bar, attached to the catch n by a joint and pin, z. P is a spiral spring, attached to the end, y, of the lever R. This spring draws the end of the lever y down, and thereby pushes the pin S towards 18, fig. 3, and through the hole 8 in the arm B, thus locking the cars together. There are two couplings exactly alike, the arm B of each being locked by the pin S of each. X is an eccentric-hook, hung on a pin, 10. The connecting-rod E is attached to this hook at 11, and to the lever D. This hook passes over the end, y, of the lever R, and when the lever D is drawn up, the lever y R is pushed out until the end, y, passes by the notch in catch n, when this catch is thrown forward under the end of the lever by the spring O, while the pin S is drawn back, all as shown in fig. 3.

Now, when a car approaches with another coupling like mine, the end, 8, of the bar B strikes the end of the trigger-bar m, and pushes back the catch n, releasing thereby the y-end of the lever R, which is drawn down by the spring P, forcing the pin S through the hole 8, thereby securely coupling the cars together. When the end of lever D is drawn up, and fastened by the ratchet W, the end, 12, of the hook X, strikes the trigger-bar m, and presses it down, so that the arm B will not hit it, and then the cars will not couple. As soon as the lever D is released, the spring 13, fig. 3, lifts the trigger-bar m up in a position where the bar B will strike it, as before described.

What I claim as my invention, and desire to secure by Letters Patent, is as follows:

A car-coupling, composed of the pin S, lever R, spring-catches and operating-devices connected therewith, for locking the arm B, all arranged in a draw-head, combined and operated as described for the purposes set forth.

ROLAN DAILY.
